UNITED STATES PATENT OFFICE

2,577,625

RETRACTABLE SIDE WALL CORE BARREL

Joseph H. Page, Houma, La., assignor of forty-five per cent to John M. Walker and ten per cent to Sam M. Hattaway, both of Houma, La.

Application June 1, 1948, Serial No. 30,255

1 Claim. (Cl. 255—1.4)

1

This device relates to a sample taking apparatus and is so constructed that a minimum number of elements are necessary to assure efficient operation thereof.

A primary object of the invention is to reduce the number of moving parts to a minimum and enable the worn parts to be readily replaced without the necessity for incurring the expense of replacing the entire tool.

A further object of the invention is to provide a sampling tool which may be readily applied at the desired place, and after taking a sample, is removed without the necessity for removing the drill pipe as well.

And yet another object of the invention is to provide a device that will efficiently take the desired sample and retain it until removed for analysis.

The invention is fully described as will herein-after appear in connection with the accompanying drawings, and the scope of the application which will be indicated in the following claim.

Figure 1 is a vertical elevation of the device of the invention in use;

Figure 2 is an enlarged fragmentary sectional view of the sample taking means in a well;

Figure 3 is an enlarged elevational view, partly in section, of the sample taking device with the core members retracted;

Figure 4 is a horizontal view taken substantially on line 4—4 of Figure 3;

Figure 5 is a horizontal view taken substantially on line 5—5 of Figure 3; and,

Figure 6 is an exploded view of the core element with a sample that has been taken.

Referring to the figures, there is shown a bore or well 10 from which a sample is to be removed. This is generally done in order to determine geological formations with respect to the presence or absence of oil, gas, water or minerals, or to determine the character of the particular area. Methods used to obtain such information before this were both tedious and costly. This has now been overcome.

A tubular string of drill pipe 12 of usual construction is inserted into bore 10, the device of the invention having been applied in a manner now to be described.

The invention is shown generally at 14 and includes a guide member 16, a sleeve 18 and a mandrel 20. As is clearly seen in Figures 2 through 4, guide member 16 is annular in construction and includes a plurality of lateral flanges 22, welded or otherwise secured to guide 16 at 24. Guide 16 is internally threaded at its lower extremity

2

at 26 to seat therein sleeve 18, threaded internally for such purposes at the lower length thereof. Sleeve 18 is threadedly counterbored at 28 in an inward taper along the inner surface for a greater portion of its length. A smooth counter-bore 30 joins threaded section 28 with a smaller smooth bore 32 at the outer end of sleeve 18, thus forming a shoulder 34, for a purpose soon to appear. Sleeve 18 is tapered as disclosed above in order to fit the threaded end 36 of any size pipe 12 that may be used.

Shoulder 34 seats mandrel 20 by means of a corresponding solid annular ring 38 slidably retained in sleeve 18. Mandrel 20 includes an upper spear-headed member 40 adapted to be grasped by the tongs 42 of an overshot 44 secured to a suitable cable 46. As the overshot forms no part of the invention, and is readily available for purchase, no further description is believed necessary. Mandrel 20 includes a lower bifurcated or forked core holding means 48 of considerable length to extend below guide 16. Mandrel 20 is slotted at its lower end to receive a pair of leaf springs 50, held in place by means of bolts 52 extending through a transverse bore in the reduced lower end 54 thereof of mandrel 20.

Leaf springs 54, of which there are two, urge core holders 56 outwardly. Core holders 56 consist of two parts, a solid rod 58 apertured at 60, and pivotally retained on forks 48 by means of pivot pins 62. The opposite ends of holders 56 include an externally threaded skirt 64 engaging an internally threaded hollow core tube 66, beveled at the outer extremity at 68 to insure penetration of the walls of a well.

In operation, sleeve 18 is secured in guide means 16 and the device is secured to the lower end of a drill or pipe 12. Mandrel 20, with core holders 56 in the position shown in Figure 3 or in dotted lines in Figure 2, is then lowered into pipe 12 until seated on shoulder 34 of sleeve 18. Mandrel 20 integrally includes or has assembled therewith, as a part thereof, the forks 48, which extend below the guide device 14 when the mandrel is seated therein. Springs 50, between the forks 48, urge the core holders 56 outwardly, with the mandrel in this position, and force them into engagement with the walls of the bore. Mandrel 20 is then removed by means of overshot attachment 44 or optionally and obviously, the string of pipe 12 with the mandrel seated therein may be removed from the well. This reverse movement causes core holders 56 to be pressed into the walls of bore 12 to gather a sample of the terrain in hollow tubes 66. Cutting edge 66

makes this operation simple and the device is removed from the well, the core 70 remaining therein by virtue of the high frictional contact with the side wall of the core tube 66. Tube 66 is then removed from rod 64 and a sample core 70 is available for analysis. Thus, there is no necessity for removing the drill pipe as has been usual heretofore and the only parts subject to wear are tubes 66 which are easily replaced.

From the above, it is seen that the several objects of the invention are attained and other advantageous results achieved.

As many modifications of the embodiment above illustrated might be made without departing from the spirit and scope of the present invention, since it is intended that the above description and accompanying claim be illustrated and not in a limiting sense.

Having described the invention, what is claimed as new is:

A wire line sidewall sampling tool for wells comprising a string of pipe in the well bore, a shoulder inside such pipe adjacent the lower end thereof, a side wall coring member including a mandrel to move down through said pipe, a co-operating shoulder on said mandrel to engage and stop on said pipe shoulder to limit downward movement of said mandrel, a lower end on said mandrel projecting below the lower end of said pipe when said shoulders are engaged, a transverse slot in said projecting end of said mandrel, a plurality of core holders disposed in said slot,

5 a pivoted connection between said core holders and said mandrel adjacent the lower end of said slot, said slot of a length to receive said core holders in upstanding inverted position, each core holder having an open core receiving end disposed upwardly in said slot as said core holder stands inverted when said mandrel is landed on said shoulder, spring means normally urging said core holders to pivot oppositely out 10 of said slot after such core holders pass out of the lower end of said pipe to engage the well bore wall, each said core holder being adapted to cut a core upon upward movement of said mandrel whereby said core holders pivot from inverted to 15 vertical position as said mandrel is raised and withdrawn back into said pipe for removal from the well while the string of pipe remains in the well bore.
